JOHN ISAAC DEVOE BRISTOL, OF CHAPPAQUA, NEW YORK.

INK-WELL.

1,277,693.

Specification of Letters Patent. Patented Sept. 3, 1918.

Application filed November 9, 1917. Serial No. 201,105.

To all whom it may concern:

Be it known that I, JOHN I. D. BRISTOL, a citizen of the United States, and a resident of Chappaqua, in the county of West- 5 chester and State of New York, have invented a new and Improved Ink-Well, of which the following is a full, clear, and exact description.

This invention relates to ink wells or 10 analogous containers for fluid and has particular reference to a holder that is adapted to retain the ink in a perfectly clean, sanitary, and fluid condition for an indefinite length of time without special attention on 15 the part of the operator.

More definitely stated, among the objects in view of this invention is the provision of 20 an ink well comprising a main base constituting a reservoir for the ink into which a tubular stem projects from a plunger or top, said top having a downwardly projecting outer flange spaced laterally from the tube and an intermediate downwardly projecting flange projecting below the edge of the first 25 mentioned flange and into a sealing fluid contained in an annular cistern in the upper portion of the base structure, the rim portions of the walls of the cistern being peculiarly formed so as to prevent any possibility 30 of the splashing or spilling of the sealing fluid.

With the foregoing and other objects in view the invention consists in the arrangement and combination of parts hereinafter 35 described and claimed, and while the invention is not restricted to the exact details of construction disclosed or suggested herein, still for the purpose of illustrating a practical embodiment thereof reference is had 40 to the accompanying drawings, in which like reference characters designate the same parts in the several views, and in which—

Figure 1 is a vertical sectional view of one form of my improved ink well, the section 45 being on the lines 1—1 of Figs. 2 and 4.

Fig. 2 is a plan view of the same.

Fig. 3 is a vertical sectional view of a modified construction, the plane being similar to that of Fig. 1; and

50 Fig. 4 is a horizontal sectional detail on the line 4—4 of Fig. 1.

In carrying out my invention in a practical and efficient form or embodiment of means, I provide a base 10 of any suitable 55 construction or design and serving to constitute a reservoir for a large quantity of

ink 11 or other fluid adapted to be dispensed in small quantities. For the sake of convenience I will refer hereinafter simply to ink as the fluid contained in the reservoir. 60 The base structure comprises a neck 12 which may be integral with the main portion of the base as indicated in Fig. 1, or which may be made as a separate part 12' and cemented or otherwise secured to the main portion of 65 the base as indicated in Fig. 3, the securing means being indicated at 13. The securing means may be a ring or layer of cement, or it may be rubber or some other means whereby the neck may be detached with convenience at any time. Except as just indicated the two structures shown in Figs. 1 and 3 are substantially alike.

The neck portion of the base is shown provided with a smooth, vertical, central 75 hole 14 of uniform cross section and indicated in this instance as of cylindrical form. Spaced outwardly from the cylindrical hole 14 is an annular open topped cistern 15 concentric with the hole 14 and adapted to 80 contain a suitable quantity of sealing fluid 16, such as mercury. Again, spaced outwardly from the cistern 15 the upper outer portion of the neck structure is provided with a smooth, cylindrical wall 17 concentric with the other features just described. 85 This wall is bounded at its lower end by means of an outwardly projecting bead 18. The upper edge or end of the wall 17 and the upper end or edge of the wall 12^a, constituting that portion of the neck structure between the cistern 15 and the central hole 14, terminate on the same level or lie in the same horizontal plane. Special attention is 90 now called to the upper end portions of the wall structures 17 and 12^a. The outer wall structure is rabbeted at 19 at its upper inner edge, and the inner wall structure 12^a is similarly rabbeted at 20 on its outer upper edge. These rabbets may be regarded as 95 enlargements at the upper end of the cistern 15 and hence constitute pockets into which the sealing fluid 16 may splash or flow, rather than splash or flow over the top of either wall and so be lost either on the outside or the inside of the reservoir in the practice of the invention. Since the 100 tendency of the sealing fluid is greater to splash or flow outwardly than it is to flow inwardly the outer pocket 19 is preferably 105 wider than the other and hence has a greater capacity.

The reader's attention is now called to the plunger or top structure indicated as a whole at 21. The plunger comprises a central tube or stem 22 having a relatively small central bore 23. Said stem in general is of cylindrical form and is fitted closely, but with an easy sliding fit, within the hole 14 of the neck. In practice I make this stem as large as possible and yet insure free sliding movement. Hence the stem may be regarded as a centering device for the entire top or plunger structure serving to hold the top from all lateral movement or tilting with respect to the base and neck portions. It is essential, however, in the practical operation of the device that air be free to pass up and down along the stem. To this end I provide one or more grooves 24 extending along the outer surface of that portion of the stem that co-operates with the wall 12^a. This insures free movement for the air without interfering with the otherwise relatively close fit between the stem and neck portions. The ribs 24', between which the grooves 24 are formed, are the parts of the stem that engage said wall 12^a, and they extend down normally within the ink reservoir, the lower end of the stem having a smooth cylindrical surface.

The central bore 23 of the plunger is preferably flared at both its upper and its lower ends as indicated at 25 and 26 respectively. The flare of this member provides a sort of funnel at 25 adapted to receive a small quantity of ink that is delivered up through the bore 23 and lower funnel 26 from the body of ink 11.

The top or plunger is provided with a downwardly projecting flange or skirt 27 parallel and relatively close to the cylindrical wall 17 above described. Between the flange 27 and the stem is another flange 28 also preferably of cylindrical form and concentric with the other flange and the stem. This flange 28, however, extends downwardly far below the lower edge of the flange 27 and into the sealing fluid 16 in the cistern 15. The flange 28 will thus be seen to project in effect down between the two pockets 19 and 20, but is spaced from the walls of said pockets and the concentric walls of the cistern so that there is no contact between the flange 28 and any part of the neck structure. The flange 28 may be regarded as projecting downwardly from a flat ceiling portion 29 consisting of two annular parts both lying in the same plane between the flange 27 and the stem 22. It will thus be seen that when the plunger is depressed in the practice of the invention the flat ceiling portion 29 just referred to will strike squarely and flatly against the upper ends or edges of the wall structures 17 and 12^a also lying in the same plane. Hence the ceiling 29 may be regarded as a positive

closure for the two pockets serving to seal said pockets against any possibility of leakage of the sealing fluid. For practical purposes this closure effect is important during the use of the invention in the normal way at each depression of the plunger under contact of the pen. However, if the plunger be held down by any suitable means against the upper ends of the wall structures 17 and 12^a and the bore 23 be plugged as by means of a match stick or the like, the ink as well as the sealing fluid will both be positively held from leakage even though the ink well as a whole may be transported in any position. I am aware that ink wells of the general type of the one set forth herein are not new, but I believe it is new with me to provide the peculiar means set forth for accommodating the flow of the sealing fluid and the prevention of loss or escape of such fluid as well as the ink. For the above purpose of transportation the ink lying in the funnel 25 will be removed prior to the plugging of the bore 23.

From the foregoing specific description of the construction, its manner of operation may be briefly set forth as follows: With the base filled with ink to any desired level which may be done at any time by simply withdrawing the plunger from the hole 14, the plunger will then be introduced with the lower end of the stem projecting into the ink. While the stem is being introduced into the ink the level in the bore 23, but for a slight capillary action, will remain the same as that of the main body of ink until the lower free edge of the flange 28 enters the sealing fluid 16. This flange and the sealing fluid at this moment constitute with the other parts of the structure an air trap, the air trapped within the flange 28 and in the upper portion of the base being then put under compression, the measure of which is the weight of the plunger. In other words the air cushion formed within the flange 28 and supported on the outside by the sealing fluid serves to buoy the plunger so as to maintain normally a space between the ceiling 29 and the upper edges of the wall structures as shown in Figs. 1 and 3. The normal level of the ink, therefore, in the bore 23 is somewhere and approximately midway between the main level of the ink in the base and the funnel 25, but far enough below the funnel so that there is no tendency for the ink to dry or harden at its only exposed surface. When, however, a pen is projected into the funnel 25 and a slight pressure is applied thereto the plunger is forced downwardly until it is stopped by the neck structure. The cushion of air within the flange 28 and the upper portion of the base will thus be put under greater compression due to the reduction in volume of the air at the pocket 20, as well as within the base due to

the larger volume of the stem entering the main quantity of ink, and so a sufficient quantity of ink is forced temporarily up through the bore to practically fill the funnel 25 or as much of it as is necessary to fill the pen. The moment, however, that the pen has been filled and removed from the funnel 25 the plunger is buoyed up again to practically its normal position and the surplus ink left in the funnel flows back into or toward the main body of ink 11.

I claim:

1. In an ink well of the character set forth, the combination of a base constituting a reservoir for ink and having a neck structure, said neck structure having a vertical hole and being provided with an annular open topped cistern surrounding and concentric with said hole, the walls bounding said cistern being rabbeted forming inner and outer concentric annular pockets constituting enlargements of the cistern, a sealing fluid contained in said cistern, and a plunger coöperating with the neck structure and characterized as follows: said plunger having a stem fitted closely in but slidable through said neck hole and provided with one or more air grooves for the free flow of air along the stem, said stem having a bore from one end to the other and said plunger being furthermore provided with a

flange spaced outwardly from and concentric with said stem and dipping into the sealing fluid in the cistern, the ceiling portion of the plunger on opposite sides of the flange just mentioned being adapted to abut squarely against the upper edges of the walls bounding said cistern pockets when the plunger is depressed.

2. In an ink well of the character set forth, the combination with a base, a neck portion therefor, said neck portion having a central vertical hole and an annular cistern surrounding said hole, the upper edges of the walls bounding said cistern terminating in exactly the same horizontal plane and being rabbeted forming enlargements or pockets for the upper portion of the cistern, the outer pocket being larger than the inner pocket, a sealing fluid contained within the cistern and a plunger having a flat ceiling portion adapted to coincide with the plane of the upper edges of said cistern walls when depressed, an annular flange projecting downwardly from said ceiling portion into the cistern and spaced from the walls thereof, and a tubular stem projecting from the plunger through the neck structure toward the bottom of the base, substantially as set forth.

JOHN ISAAC DEVOE BRISTOL.
